(57) **CLAIM**

The ornamental design for a thermally isolated high intensity light source with spacers, as shown and described.

DESCRIPTION

FIG. 1 is a top, front, right perspective view of a thermally isolated high intensity light source with the bulb, sleeve, spacer clips, and connectors in an assembled configuration; FIG. 2 is a bottom, front perspective view thereof; FIG. 3 is a right view thereof; FIG. 4 is a left view thereof; FIG. 5 is a bottom view thereof; FIG. 6 is a front view thereof, the rear view being a mirror view thereof; FIG. 7 is a top view thereof; FIG. 8 is an exploded view of FIGS. 1-7, illustrating the separate components thereof that are the bulb, sleeve, spacer clips and connectors (see FIGS. 9-12 for the connectors and FIGS. 13-19 for the spacer clips), it being understood that the pair of spacer clips are identical to each other and the pair of connectors are identical to each other; FIG. 9 is a top, front, left perspective view of the connector of FIGS. 1-8; FIG. 10 is a bottom, rear, left perspective view thereof; FIG. 11 is a top, front, right perspective view thereof; FIG. 12 is a bottom, rear, right perspective view thereof; FIG. 13 is a top perspective view of the spacer clip of FIGS. 1-8; FIG. 14 is a bottom perspective view thereof; FIG. 15 is a top view thereof; FIG. 16 is a front view thereof, the rear view being a mirror image thereof; FIG. 17 is a right side view thereof, the left side view being a mirror image thereof; and, FIG. 18 is a bottom view thereof.

1 Claim, 8 Drawing Sheets
